[57] CLAIM

The ornamental design for an infant toy, as shown and described.

DESCRIPTION

FIG. 1 is a front perspective view of an infant toy showing my new design;

FIG. 2 is a front or rear elevation thereof;

FIG. 3 is a left or right side elevation thereof; and

FIG. 4 is a top or bottom plan view thereof.

The broken line showing of a figure is for illustrative purposes and forms no part of the claimed design.
